UNITED STATES PATENT OFFICE.

WILLIAM A. BRUBAKER AND FERDINAND F. BRUCKER, OF AKRON, OHIO.

BEAD-FORMING MACHINE.

1,192,383.

Specification of Letters Patent.

Patented July 25, 1916.

Application filed February 23, 1916. Serial No. 79,957.

To all whom it may concern:

Be it known that we, WILLIAM A. BRUBAKER and FERDINAND F. BRUCKER, citizens of the United States, residing at Akron, Ohio, have invented certain new and useful Improvements in Bead-Forming Machines, of which the following is a specification.

Our present invention relates to improvements in machines for forming rolls or beads at the edges or open ends of tubular rubber articles and is shown and described in the present instance as adapted more particularly for rolling beads on the ends of the tubular neck or stems of toy balloons, though not limited to this specific use.

The invention has, among its objects, to provide a simple, economical, efficient and durable machine which will roll such beads in an automatic manner with great rapidity and without danger of injury to the rubber composition of which the articles are made.

Our said invention includes the novel features of construction and arrangement and combination of parts hereinafter described and particularly defined by the appended claims.

In the embodiment of our invention illustrated in the accompanying drawings, Figure 1 is a plan view with the table partly broken away. Fig. 2 is a sectional elevation, with parts omitted. Figs. 3 to 5 are detail views.

The articles upon which the beads are to be rolled are mounted upon the forms or cores indicated at A, designed to be applied to an endless moving carrier and to be brought thereby successively into co-operative relation to the bead rolling means. The endless moving carrier may conveniently take the form of a rotary table 1 revolving continuously during the normal operation of the machine, in the direction of the arrow indicated in Fig. 1, and steadied or supported by rollers 1^x suitably mounted on the frame.

Motion may be imparted to the table by any suitable means, such for example, as worm wheel 2 fast on the vertical shaft 3, which supports the table. This worm wheel 2 meshes with a worm 4 fast on a horizontal shaft 5 journaled in suitable bearings 6 and 7, which at its outer end carries a rigidly attached worm wheel 8 which in turn meshes with a worm 9 fast on drive shaft 10. This drive shaft may be driven from any suitable source of power as for instance an elec-

tric motor, (not shown) by means of a belt 11^a passing over belt pulley 11.

Arranged circumferentially of the table is a series of swinging arms 12, pivoted 60 to the under face of the table at 12^a and swung normally outward in the position shown on the upper part of Fig. 1 by springs 13 connected respectively to eye bolts carried by the arms 12 and to the table. 65 In the outer ends of these arms are journaled the supports or holders for the forms for the articles to be treated. These are in the form of spools 14 having a central spindle 14^a adapted to engage a central bore in the form or core and an offset pin or projection 14^b designed to engage a notch or recess in the lower edge of said form or core whereby the latter is held against rotation relative to the spool. 70

The table is provided with a plurality of slightly curved slots 1^a extending inward from its peripheral edge, which slots 1^a receive the narrow or reduced portions 14^c of the spools or supports 14. The spools have 80 downwardly extending shanks journaled in the arms 12 near their outer ends and fast on said shanks below said arms are the pulleys or sprockets 15 designed to rotate said form supports at the proper time to co-operate with the bead rolling mechanism herein-after more fully described. 85

The form or core carrying the article to be treated having been placed on the carrier the portion of the article is to be first subjected to the action of a brush or like device. This is indicated at 16 and is arranged to act upon the article before the carrying arm has been swung inwardly toward the axis of the table. The brush is preferably carried by an arm 17 pivoted to a post 17^a fixed to bracket 18 and acted upon by a spring 17^b. Backward movement of the brush arm is prevented by a set screw 17^c of arm 17 bearing against a lug 18^a carried by post 17^a. 100 The function of the brush is to effect the engagement of pin 14^b with the notches or recesses of the cores. The arms are swung inward toward the axis of the table to bring them into proper position to be acted upon by the bead rolling mechanism by a curved guide 20 acting on the spindle support 12 but before reaching this point it is desirable that means shall be provided to insure the proper seating of the forms on the carriers, 105 and also that they shall be held down upon the carriers during the action of the bead

2
forming roll which in order to roll the bead has to exert an upward pressure on the rubber form or article.

The means for holding the forms down upon carriers comprises a guide plate or ring 21 secured to the upper face of the table by brackets 22 and arranged concentric with the edge of the table. Said guide plate is spaced sufficiently from the upper face of the table to permit the passage therebetween of the annular flanges formed at the bases of the forms. This guide plate 21 has recessed portions 21^a corresponding to the slots or recesses 1^a in the table edge, to permit the forms to extend therethrough.

The means for detecting or ascertaining whether the forms are properly seated on the arms before they are swung into said recesses, in the embodiment shown in the drawings, comprises a lever arm 23 having an upwardly curved or inclined end 23^a adapted to engage with the upper faces of the flanges of the forms. This arm 23 is freely pivoted on a stationary axis 23^d and is sustained in a substantially horizontal position by an adjustable stop such as set screw 24. An arm 23^b which may form a continuation of said arm 23 is provided with a lug 23^c adapted to form a stop for spring 25 pressed rod 25 guided in brackets 26 and tending, under action of spring 27 to move toward the left. The opposite end of this rod is adapted to operate means for stopping the machine. Where the apparatus is driven by an electric motor such stopping means may take the form of a pin 25^a adapted to normally rest behind the handle 28 of the switch, which controls the supply of current to the driving motor.

40. The arms are swung inward toward the table to bring the carriers and forms into the recesses in the table guide or presser plate by a guide 20 curved concentrically with the table and having an initial inclined or convex portion which engages suitable bearing portions of the carriers and swings them inward toward the axis of the table and holds them in this position while they are being rotated to enable the bead forming roller to roll or form the bead.

The carriers may be provided with anti-friction rollers to coact with the guide 20.

The spindles are rotated to impart a revolving motion to the forms by means such as an endless belt or chain 30 passing over sprockets 31 and 32, the latter of which is fast on a shaft 33 journaled in a suitable bearing in bracket 34. This shaft has keyed or otherwise secured to its lower end a gear 35 which meshes with a gear 36 fast to a second vertical shaft 37 journaled in said bracket 34. This shaft 37 carries at its upper end a miter gear 38 which meshes with a miter gear 39 on the drive shaft 10. Provision may be made for applying sufficient

tension to the chain 30 by sprocket 31 from a bracket 40 slidably secured to the main frame or base of the machine, the requisite tension being secured by set screw 40^a.

We find the best results are secured by 70 having the portion of the belt or chain which acts on the driving portions of the spindles travel in the same direction as the table but at a greater speed. To prevent any slipping and to give a positive drive we 75 preferably form the endless belt in the shape of a sprocket chain meshing with sprocket wheels 15 fast on the spindles.

The device which acts on the revolving forms to roll the beads comprises a roller 80 41, preferably of cone or truncated cone shape, and having a removable covering of soft rubber or analogous material indicated at 41^a. This roller is supported from one end only and inclines upwardly with relation to the plane of the table and with its free end pointing in the direction of rotation of the table. Said roller 41 is supported and operated by a rotating shaft 42 and is preferably detachably connected to said shaft by having a stem 41^b fitting in a socket in the end of shaft 42 and secured therein by set screw 42^a. Said shaft 42 is journaled in bearings carried by the arms 43^a and 43^b of a forked bracket 43 through which passes 85 rotatable shaft 44. Said bracket is therefore 90 rotatably supported by said shaft and the bearing 45 of said shaft. A spring 46 connected respectively to bearing arm 43^b and to a relatively fixed lug 47 tends to keep the 100 roller pressed against the successive forms with a yielding pressure.

Bearing member 45 has its lower end mounted to oscillate on a horizontal drive shaft 48 journaled in the main frame or 105 base of the machine, and said member is provided with an extension or arm 49 which has a slot through which passes a fixed vertically disposed threaded post 50. This holds said arm and bearing member 45 110 against rotation about said shaft 44, but enables the inclination of said bearing member 45 and said shaft 44 to be varied through means such as lock nuts and washers on said rod 50, and by this means the inclination of 115 roller 41 to the plane of the table may be varied. Lug or projection 47 is conveniently carried by a bar 51 secured to arm 49 and said bar also carries another lug or projection 52 through which passes a set screw 120 52^a serving as an adjustable stop to limit the backward swing of the bracket 43^b. Shaft 42 carries a bevel gear 52^b which meshes with a bevel gear 52^c carried at the upper end of shaft 44. This shaft carries 125 at its lower end a bevel gear 54 which meshes with a bevel gear 55 fast on a shaft 48 provided with driving means such as belt pulley 56 adapted to be driven from belt pulley 57 130 on shaft 10 through the belt 58.

Having thus described our invention, what we claim is:—

1. A machine of the class described comprising a conveyer, form carrying devices 5 rotatably carried by said conveyer, an inclined rotary bead forming roll mounted in proximity to said conveyer to swing toward and from said forms, pressure means normally forcing said roll yieldingly toward the forms, means for rotating said roll, and means for rotating the forms as they travel past said roll.
2. A machine of the class described comprising a conveyer, form carrying devices 15 rotatably carried by said conveyer, an inclined rotary bead forming roll mounted in proximity to said conveyer to swing toward and from said forms, pressure means normally forcing said roll yieldingly toward the forms, means for holding the forms in place on the form carrying devices, means for rotating said roll, and means for rotating the forms as they travel past said roll.
3. A machine of the class described comprising a conveyer, form carrying devices, 25 forms adapted to be placed on said devices to interlock therewith, a rotary bead forming roll having its upwardly moving surface adapted to act on the article carried by the form near its lower edge, said roll having its axis inclined to the plane of the conveyer, means for holding the forms in locking engagement with the carrying devices while subjected to the action of the bead 30 forming roll, and means controlled by the position of the forms on the carrying devices to stop the movement of the machine in case a form is not properly seated on its carrying device.
4. In a machine of the character described, 40 a rotary table, annularly arranged form carrying devices rotatably carried by said table, a roll shaft mounted approximately tangential to the periphery of said table, and having a free end spring pressed toward the forms carried by said table, a bead forming roll carried by the free end of said shaft, said roll and shaft inclining upwardly with relation to the plane of the table, means for holding the forms on said form carrying devices, means for rotating the form carrying devices, and means for rotating said forming roll.
5. A machine of the class described comprising a conveyer, form carrying devices supported thereby, forms adapted to be placed on said form carrying devices to have non-rotatable connection therewith, means adapted to act on said forms to effect said non-rotatable connection, a spring pressed bead forming roll having its axis inclined to the plane of the conveyer for acting on the articles carried by the forms, and means for rotating the carrying devices while they are so acted upon.
6. A machine of the class described comprising a conveyer, rotatable form carrying devices carried thereby having spindles to engage axial recesses in the forms and offset projections to engage corresponding offset recesses in the forms, means for imparting a rotary movement to said forms on the carriers to effect engagement of the offset projections and recesses, an inclined rubbing roll for acting on the material on the forms, 75 means for rotating said rubbing roll, and means for rotating the form carriers during the action of said rubbing roll.
7. A machine of the class described comprising a conveyer, rotatable form carrying devices carried thereby having spindles to engage axial recesses in the forms and offset projections to engage corresponding offset recesses in the forms, a stationary brush having bristles projecting into the path of 80 movement to said forms on the carriers to effect engagement of the offset projections and recesses, an inclined rubbing roll for acting on the material on the forms, means for rotating said rubbing roll, and means 85 for rotating the form carriers during the action of said rubbing roll.
8. A machine of the class described comprising a conveyer, rotatable form carrying devices, means for holding the forms thereon in interlocked engagement therewith, means for rotating the form carriers during a portion of their travel with the conveyer, a roll shaft having a free projecting end, a bead forming roll removably carried 100 on said end and adapted to coact with the articles on the forms, means for pressing said free end toward the forms, and means for driving said shaft.
9. A machine of the class described comprising a conveyer, rotatable form carrying devices, means for holding the forms thereon in interlocked engagement therewith, means for rotating the form carriers during a portion of their travel with the conveyer, a roll shaft having a free projecting end, a bead forming roll removably carried 110 on said end and adapted to coact with the articles on the forms, a yoke having arms in which said shaft is journaled, a 115 driving shaft projecting through said yoke and having bevel gearing connecting it to said roll shaft, and a spring acting on one of the arms of said yoke.
10. A machine of the class described comprising a conveyer, rotatable form carrying devices, means for holding the forms thereon in interlocked engagement therewith, means for rotating the form carriers during a portion of their travel with the conveyer, a roll shaft having a free projecting end, a bead forming roll removably carried 125 on said end and adapted to coact with the articles on the forms, means for supporting said roll shaft with its axis inclined to the 130

plane of the conveyer, driving means for said roll shaft, and means for varying the inclination of said shaft without disturbing the driving connections thereto.

5 11. A machine of the class described comprising a conveyer, rotatable form carrying devices supported thereby, means for rotating the form carriers during a portion of their travel with the conveyer, a roll shaft 10 having a free projecting end, a bead forming roll carried thereby, a pivoted yoke having arms provided with bearings in which said shaft is journaled, yielding means tending to rock said yoke in one direction, a 15 shaft projecting through said yoke and operatively connected with said roll shaft, a bearing member for said shaft, a drive shaft about which said bearing is adapted to oscillate, said drive shaft having driving connections with said first named shaft, and 20 means for adjusting the position of said bearing member.

12. In a machine of the character described, a rotary table having recessed edges, 25 a plurality of arms pivotally connected to

the table near said recesses, form carriers carried by said arms, forms having bases adapted to interlock with said form carriers, a stationary guide for swinging said arms toward the table to cause the form carriers to enter the recesses as the table rotates, means carried by the table to overlap portions on the forms to hold them on the form carriers, a rotating bead forming roll adapted to contact with the articles 30 on the forms, and means for rotating the form carriers while traveling past said bead forming roll.

13. A machine of the class described comprising an endless moving conveyer, form carrying devices rotatably carried by said conveyer, a rotary bead forming roll for engaging the articles on said forms, and an endless moving drive belt having a portion in driving relation to said spindles and 40 moving in the same direction as the spindle conveyer and at a greater speed.

WILLIAM A. BRUBAKER.
FERDINAND F. BRUCKER.
